CLAIM

The ornamental design for liquid dispensing spout, as shown.

DESCRIPTION

FIG. 1 is a top perspective view of a liquid dispensing spout, showing my new design;
FIG. 2 is a top plan view thereof;
FIG. 3 is a bottom plan view thereof;
FIG. 4 is a top perspective view of a second embodiment of that shown in FIG. 1;
FIG. 5 is a top plan view thereof;
FIG. 6 is a bottom plan view thereof;
FIG. 7 is a top perspective view of a third embodiment of that shown in FIG. 1;
FIG. 8 is a top plan view thereof;
FIG. 9 is a bottom plan view thereof;
FIG. 10 is a top perspective view of a fourth embodiment of that shown in FIG. 1;
FIG. 11 is a top plan view thereof;
FIG. 12 is a bottom plan view thereof;
FIG. 13 is a top perspective view of a fifth embodiment of that shown in FIG. 1;
FIG. 14 is a top plan view thereof; and
FIG. 15 is a bottom plan view thereof.
